(57) **CLAIM**

The ornamental design for a control lever for earth moving machines, as shown and described.

DESCRIPTION

FIG. 1 is a right side view of a control lever for earth moving machines;

FIG. 2 is a front view of a control lever for earth moving machines;

FIG. 3: is a rear view of a control lever for earth moving machines;

FIG. 4: is a left side view of a control lever for earth moving machines;

FIG. 5: is an upper view of a control lever for earth moving machines; and,

FIG. 6: is a bottom view of a control lever for earth moving machines.
